UNITED STATES PATENT OFFICE.

ARTHUR L. SHAW, OF CHICAGO, ILLINOIS.

CONVEYER.

1,180,948.

Specification of Letters Patent. Patented Apr. 25, 1916.

Application filed April 1, 1915. Serial No. 18,441.

To all whom it may concern:

Be it known that I, ARTHUR L. SHAW, a citizen of the United States, residing at Chicago, in the county of Cook and State 5 of Illinois, have invented certain new and useful Improvements in Conveyers, of which the following is a specification.

My invention relates to improvements in conveyers of the chain and drag type and 10 means for supporting and moving them from place to place.

Another object of my invention is to generally improve structures of this character whereby to simplify the design and cheapen 15 the cost of construction and to provide co-operating means for their support whereby the said devices may be moved from place to place and adjusted to new situations by means readily operable by a single work- 20 man.

Other, further and more specific objects of my invention will become readily apparent, to persons skilled in the art, from a consideration of the following description when taken in conjunction with the drawings, wherein:—

Figure 1 shows an elevation of one form which the invention may take. Fig. 2 is an isometric perspective of a tower for supporting the conveyer. Fig. 3 is an end elevation of a stationary track whereon to support the conveyer. Fig. 4 is a side elevation of the same.

In all the views the same reference characters are employed to indicate similar parts.

While my conveyer can be employed for handling and conveying various substances, or materials, it is especially well adapted 40 for conveying coal from railway cars into bins or from bins to cars; from yards to wagons or trucks, and from wagons and the like to bins or cars, and I will describe it in connection with such use.

45 The invention lies not so much in the specific construction of the conveyer as in its adaptation to a power driving motor and the combinative coöperation of the motor and conveyer for ease of handling and the 50 means of supporting and transporting the conveyer with its attached motor, from place to place, ready for immediate operation when located in new situations.

In handling coal, at coal yards, cars of 55 coal are unloaded into bins placed in rows along and parallel with railway tracks and

from the bins the coal is subsequently loaded on wagons and trucks for distribution.

In carrying my invention into effect I provide convenient means for supporting 60 the conveyer and whereby or whereon it may be moved to various localities where its use is required.

The conveyer proper consists of a sub-frame 10 and a superposed frame or trough, 65 11. These spaced apart frames are parallel and in the same vertical planes. The sub-frame consists of parallel angle bars properly spaced apart and connected together at intervals by cross bars. A sheet 70 metal trough 17, is the conduit through which the materials are conveyed by the chain driven drags. The trough 17 and the angle irons of the sub-frame are connected together by vertical angle irons or posts, 22, 75 23', 24'. The posts or standards 23', 24' rise above the conveyer trough for support of an internal combustion engine, or other motor, 26. Cross braces, 27, connect the standards 23' and 24' on either side of and above the 80 frame structure. A floor 29 is supported upon the upper end of the standards upon the angle irons 31. Across the front end of the structure, to the standards are secured suitable shaft bearings for accommodation of the chain driving shaft 34. The shaft 34 projects from one side of the 85 frame and on the projecting end it carries a sprocket wheel 35 for the drive chain 36. The drive chain 36 is connected to a sprocket 90 wheel 37 that is driven by a counter shaft 38. Secured to the counter shaft 38 is a gear wheel which meshes in a pinion 42 carried on the engine shaft 43. Mounted on the shaft 34 are sprocket wheels for conveyer chains. Connected to the conveyer 95 chains 48, at proper intervals are conveyer drags 50.

Mounted upon the standards at the lower end of the conveyer are suitable shaft bearings for the respective ends of a shaft 54. The shaft 54 carries sprocket wheels near its ends, for the conveyer chains 48.

The operation of the conveying device is obvious from the foregoing description, in 105 connection with the drawings.

The motor 26 being operated in the proper direction propels the conveyer chains. A bail 68 is pivotally secured to either side of the structure, as at 69, at points where the 110 structure will substantially balance, as shown in the drawings, the bail carrying an eye 71

into which a hook 72 of a pulley block 73 is adapted to engage. When the device is raised by the pulley block, as shown in Fig. 1, it is substantially balanced and may be 5 easily and conveniently handled by a single operator, for moving the conveyer along in front of a series of bins 75. The trolley upon which the device is moved consists of trolley wheels 76—76 rotatably supported in 10 a vertically extending frame 77, as at 78, the lower end of which is bifurcated and in-turned as at 79, to the ends of which immediately below the track 80 is a cross bar 77'. In the cross bar 77' is secured rod 80, 15 linked to rod 81, as at 82. The lower rod 81 carries an eye 83 into which the block 84 is adapted to be hooked or to engage. Along the side of the bins 75—75 at proper intervals I erect posts 85 of proper and sufficient height, to which is attached an equal 20 number of inclined rafters or beams 86, the lower ends of which are connected to the roof 87 of the bin structure, as at 88. Braces 89 are connected to the vertical posts 85, as 25 at 90, the upper projecting ends of which are connected to the rafters 86, as at 91, and other braces 92 and 93 are connected to each of the vertical posts 85 and to the rafters 86, as shown. A metal plate 94, is secured 30 to the forwardly projecting ends of each of the rafters 86, and is provided with a vertically extending end 95 which is secured to the trolley track or rail 80 as by bolts 96. Cross braces 98 join adjacent posts 85. By 35 this means the conveyer may be moved along the track upon which are located the cars of coal to be loaded or unloaded and in front of the respective bins 75—75. Owing to the presence of the turn bolt eye 79' which 40 passes through the cross bar 77', the conveyer may be rotated upon the vertical axis of the support.

When it is desired to transport the conveyer in the coal yard or other places I support it upon a tower 100 consisting of vertical standards 101, 102, 103, and 104, connected together by a quadrilateral frame 105, at the top and cross bars 106, to the center of which is rotatively secured a hook or eye bolt 107. The standards 101 and 102 are cross-braced by braces 108 and transverse braces 109. In the same manner standards 103 and 104 are braced and cross connected. The standards 102 and 104 are cross connected together near their bottom ends by the braces 110 and the cross brace 111. A quadrilateral frame 112 connects all of the standards together. The standards 101 and 103 are similarly connected together, but at their 55 tops by other braces 110 and 111. The cross bars 111 afford a support for the conveyer,

as shown in Fig. 1, when the same is resting upon the tower, and the cross bar 111 at the top is never in the path of the conveyer when it is lifted to its highest extent. The tower 65 100 is preferably supported upon a truck 113, which may be moved from place to place by the handle or tongue 114. An apron 115 may be secured to the front end of the conveyer, as at 116, upon which the coal or other 70 material handled by the conveyer will fall on its way to the receptacle in which it is intended to be placed, such as wagons, trucks or the like.

While I have herein shown and described 75 a single embodiment of my invention for the purpose of clear disclosure, it is evident that many changes in the arrangement and disposition and configuration of the parts may be made within the scope of the appended 80 claims, and that a motor, other than a gas engine may be employed, such as an electric motor or the like, for driving the conveyer.

Having described my invention, what I 85 claim is:—

1. In a device of the character described, the combination with a drag conveyer, a rigid frame supporting said conveyer, a motor supporting frame carried by the conveyer frame near the receiving end thereof, 90 a motor mounted thereon, a drive chain connecting the motor to the conveyer at the discharge end thereof, and a supporting bail pivotally connected to opposite sides of the conveyer frame between the motor and the 95 discharge end at points to substantially balance the structure when supported by the bail.

2. In a device of the character described, the combination with a drag conveyer, of a 100 conveyer trough, a sub-frame spaced beneath and away from the trough to carry the return flight of the conveyer, braces connecting the trough and sub-frame, certain of said braces adjacent the receiving end of the conveyer being extended above the trough to provide a motor supporting frame, a motor carried on said extended braces, a drive chain connecting the motor to the conveyer at the discharge end and a supporting bail 110 pivotally connected to opposite sides of the trough between the motor and the discharge end at points to substantially balance the structure when supported by the bail.

In testimony whereof I hereunto set my 115 hand in the presence of two subscribing witnesses.

ARTHUR L. SHAW.

In the presence of—

STANLEY W. COOK,
MARY F. ALLEN.
